U.S. Appl. No. 29/681,371, filed Feb. 25, 2019, Etgar et al.

Primary Examiner — Cynthia R Underwood

(74) Attorney, Agent, or Firm — Sheridan Ross P.C.

(57) **CLAIM**

The ornamental design for the beverage container, as shown and described.

DESCRIPTION

FIG. 1 is a perspective view of a beverage container;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

The broken lines in the drawings illustrate portions of the beverage container which form no part of the claimed design.
